UNITED STATES PATENT OFFICE.

JOHN A. REED, OF MORVIN, ALABAMA.

BICYCLE-FRAME.

SPECIFICATION forming part of Letters Patent No. 617,604, dated January 10, 1899.

Application filed January 12, 1898. Serial No. 666,449. (No model.)

To all whom it may concern:

Be it known that I, JOHN A. REED, a citizen of the United States, residing at Morvin, in the county of Clarke and State of Alabama, have invented certain new and useful Improvements in Bicycle-Frames; and I do hereby declare the following to be a full, clear, and exact description of the invention, such as will enable others skilled in the art to which it appertains to make and use the same.

This invention has reference to a novel construction in a bicycle, and it relates more especially to the structure of the bicycle-frame, the object being to provide an adjustable frame which can also be taken apart quickly and conveniently, so that it can be packed in a small compass for transportation or otherwise.

A further object of the invention is to furnish improved means for adjusting the saddle.

The invention consists in the features of construction hereinafter described and specifically claimed.

In the accompanying drawings, forming part of this specification, Figure 1 is a side elevation of a bicycle-frame constructed in accordance with this invention. Fig. 2 is a top plan view. Fig. 3 is a vertical longitudinal section taken on the line 3-3 of Fig. 2. Fig. 4 is a horizontal section taken on the line 4-4 of Fig. 1.

Referring now to said drawings, 1 indicates the steering-head, and 2 the steering-post. The stem 3 of the handle-bars is straight and extends into the steering-post 2, while on its rear side it is provided with a longitudinal groove 4, it being understood that the stem fits snugly within said post. The cap 5 holds the upper set of balls in place, and it is held in place by a jam-nut 6. A set-screw 7 extends through said cap 5 and through an opening 8 in the upper end of the steering-post and enters the groove 4 in the stem 3. In this way it is seen that the set-screw can be clamped tight to hold the handle-bars in the correct position; but when it is desired to raise the handle-bars the said set-screw can be loosened to allow the stem 3 to move longitudinally, it being obvious that the stem 3 will not turn, owing to the fact that the end of the set-screw 7 is situated within the longitudinal groove 4 therein. The cap 5 is pro-

vided with a plurality of screw-threaded openings 9, so that the cap can be turned to compensate for wear and yet permit the set-screw 7 to be inserted.

The frame of the bicycle is similar to what is known as the "diamond" frame—that is to say, it is provided with a top frame 10, the lower frame 11, the backstays 12, the back fork 13, and the diagonal frame 14. These parts are connected together in an adjustable and also separable manner, so that the frame of the bicycle cannot only be adjusted, but the frame can be quickly taken apart and dismembered. There are two top frames or bars 10 and their front ends enter the sockets 15, that project rearwardly from the steering-head. The front ends of these bars 10 are held within the sockets by means of set-screws 16, while the rear ends of the bars 10 extend through openings in a seat-block 17 and are held rigid with relation thereto by the set-screw 18. To the rear ends of the bars 10 are secured coupling-fingers 19, such construction 75 preferably comprising a bifurcated rear end of the bar 10, between which the reduced forward end of the coupling-finger is pivoted. The backstays 12 are hollow and their upper ends receive the fingers 19, while said stays are provided with set-screws 20 for holding said coupling-fingers in place. Near the rear end of the back fork are the upright projections 21, to the upper ends of which the lower ends of the backstays are pivoted. The crank-hanger 22 is provided with rearwardly-extending fingers 23, that enter the forward ends of the sides of the fork 13, the forward ends of the sides of the fork being socketed and provided with set-screws 24 to engage said fingers 23. On the front side of the crank-hanger there is a finger 25, that enters the lower socketed end of the lower frame 11 and is held therein by a set-screw 26. The upper end of the lower frame 11 enters the socket 27, projecting rearwardly from the steering-head, and which is also provided with a set-screw 28 to engage the upper end of said lower frame. The seat-block 17 is provided with the upright opening 29 about midway between its ends to receive the socket or tube 30. This socket or tube is provided with an opening 31 on its rear side, through which the set-screw 32 extends, whereby said set-screw serves to hold

both the seat-stem 33 and said socket 30 rigid with relation to said seat-block 17. To the lower end of the socket 30 the diagonal frame 14 is pivoted, the lower end of said frame being pivoted to the upper end of an upright projection 34 upon the crank-hanger.

It will be seen from the foregoing description that a bicycle-frame constructed in this manner can be readily adjusted, as is obvious, 10 and, furthermore, that it can be quickly taken apart by loosening the several set-screws referred to.

Having thus described my invention, what I claim as new, and desire to secure by Letters 15 Patent, is—

1. The combination with the steering-head of a bicycle-frame, the steering-post provided with an opening and the cap at the upper end of said steering-head provided with a plurality 20 of screw-threaded openings to receive a set-screw, of the stem of the handle-bars extending into said steering-post and provided with a longitudinal groove to receive said set-screw.

2. In a bicycle-frame, a steering-head with 25 which the front ends of the top and lower frames are adjustably and separably connected, the backstays pivotally, adjustably

and separably connected with the rear end of the top frame and pivoted at their lower ends to the rear end portions of the back fork, of 30 said back forks adjustably and separably connected at their forward ends with the crank-hanger, said crank-hanger being adjustably and separably connected with the lower end of the lower frame, and the diagonal frame 35 pivotally connected at its upper end with the top frame and at its lower end with the crank-hanger.

3. In a sectional bicycle-frame the several parts of which are relatively adjustable, the 40 seat-block adjustably mounted upon the top frame and provided with an opening, a socket-piece extending through said opening, a set-screw, and the diagonal frame pivotally connected with the lower end of said socket-piece 45 and pivotally connected at its lower end with the crank-hanger.

In testimony whereof I affix my signature in presence of two witnesses.

JOHN A. REED.
